Fig. 8.

FIG. 9.

FIG. 10.

This technical drawing illustrates a mechanical assembly, possibly a track or frame component. The drawing shows a base structure with several labeled parts: 69, 68, 67, 65, 55, 66, 59, 60, 58, 57, 62, 63, 50, 53, and 11. The parts are rendered with different hatching and shading to distinguish them. The overall shape is elongated and curved, with various cutouts, notches, and protrusions.

UNITED STATES PATENT OFFICE.

ORION K. TILLMAN, OF HORNER, WEST VIRGINIA.

DOOR-LOCK.

1,264,224.

Specification of Letters Patent. Patented Apr. 30, 1918.

Application filed June 8, 1917. Serial No. 173,589.

To all whom it may concern:

Be it known that I, ORION K. TILLMAN, a citizen of the United States, residing at Horner, in the county of Lewis and State 5 of West Virginia, have invented certain new and useful Improvements in Door-Locks, of which the following is a specification.

This invention relates to locks and the primary object of the invention is to provide a lock which will effectually resist all efforts to open the door from the outside except by the use of a proper key. The invention seeks to produce a lock which may be applied to a door either as a mortise lock 15 or a rim lock and which will be equipped with a dead latch controlled primarily by gravity which may be easily set to prevent manipulation of the latch to open the door from the outside. A further object of the 20 invention is to provide means for the escape of dust which may possibly work into and collect in the casing, and a still further object is to provide a lock in which the bolt may be readily manipulated by the insertion 25 of a properly fitted key but cannot be manipulated by a skeleton key or a bent wire or other implement. A still further object of the invention is to produce a latch bolt which may be readily inverted or re- 30 versed so that the lock may be applied to either a right handed or left handed door.

The invention is illustrated in the accompanying drawings, in which—

Figure 1 is a side elevation of a portion 35 of a door having my improved lock applied thereto as a mortise lock;

Fig. 2 is an edge elevation of the door having the lock arranged as shown in Fig. 1;

Fig. 3 is a view of the gravity dead latch shown in Fig. 1, the parts being arranged to prevent rotation of the knob spindle and consequent release of the latch;

Fig. 4 is a sectional elevation, the section 45 being taken on the line 4—4 of Fig. 2;

Fig. 5 is a detail perspective view of the dead latch shown in Figs. 1 and 3, the face plate of the casing being in position;

Fig. 6 is a horizontal section on the line 50 6—6 of Fig. 1;

Fig. 7 is a similar view with the lock applied as a rim lock;

Fig. 8 is an elevation of the lock applied as a rim lock;

Fig. 9 is a detail perspective view of the 55 dead latch members shown in Fig. 8;

Fig. 10 is a transverse section on the line 10—10 of Fig. 8;

Fig. 11 is a detail perspective view of the bolt and the tumblers coöperating therewith, this figure showing the side of the bolt opposite that appearing in Fig. 4;

Fig. 12 is a detail perspective view of the 60 knob-spindle-engaging member of the dead latch shown in Fig. 1.

The reference numeral 1 indicates a portion 65 of a door having a mortise 2 formed therein, the outer or open side of said mortise being covered by a mortise plate 3 in the usual manner.

Within the mortise, I fit the lock casing 4 which will be constructed of metal plates joined together by stud bolts as is now the general practice. Openings for the passage 70 of a knob spindle 5 are provided in the side plates of the casing and in the door and within the casing a hub 6 is fitted upon the knob spindle so that any rocking or rotary movement imparted to the knob spindle will be transmitted directly to the hub. The 75 knobs 7 are secured upon the ends of the spindle 5 and the openings to receive the fastening screws may extend entirely through the sockets of the knobs so that if a screw should be lost, a nail or pin may be 80 inserted so as to retain the knob on the spindle securely. The outer end of the knob spindle is enlarged, as shown at 8, so that the diameter of this end of the spindle will 85 be greater than the diameter of the opening 90 through which the spindle passes. Consequently, the attempts of a burglar or house-breaker to obtain access to the dwelling by removing the knob and then forcing the spindle through the lock will be frustrated. 95 The hub 6 is journaled at its ends in the lock casing and is constructed with a radial lug or tooth 9 which is adapted to engage a notch 10 in the latch bolt 11 so that rotation 100 of the knob spindle will actuate the said bolt. The latch bolt is shown most clearly in Fig. 8, in which figure it will be noted 105 that the said bolt is constructed at its outer end with a tongue 12 adapted to project through the opening in the mortise plate 3, said end being beveled, as shown at 13, so that the latch may ride readily upon the lock strike. It will also be noted that the

body of the bolt is constructed with an elongated opening 14 whereby the bolt may slide past the hub 6 and the knob spindle and a notch 10 is provided in both the upper and the lower wall of said opening or slot so that whichever wall of the slot is uppermost, the bolt may be operatively engaged by the hub. The bolt is furthermore constructed in each side edge near its inner end with a notch 15 and between the said notch and its front end a recess 16 is provided in each edge of the latch bolt. It will thus be seen that the latch bolt is symmetrical and may be readily reversed within the lock casing so that the lock 10 may be applied to any door whether the door swings to the right or to the left. A spring 17 is secured to the inner wall of the lock case below the latch bolt and has its upper free end bearing against the inner end of 20 said bolt so that the force of the spring is exerted to hold said bolt in engagement with the socket 18 in the door frame and projected through the strike plate 19. Below the latch bolt, I pivotally mount within the lock 25 case a gravity pawl or dog 20 which is mounted upon a stud pivot 21 at its lower inner corner and is provided at its inner upper corner with a tooth or spur 22 adapted to engage the notch 15 in the lower edge of 30 the latch bolt. Upon reference to Fig. 4, it will be seen that the greater weight of this dog is disposed at the front of its pivot so that it tends to drop and thereby acts upon the bolt to project the same. The lock case 35 will be provided with internal shoulders 23 to limit the outward movement of the bolt and thereby prevent breakage of the same or damage to either the dog or to the frame.

It will be noted that in the drawings, the 40 latch bolt is shown projected by the action of both a spring and a weight and is furthermore so operatively connected with the knob spindle that it may be projected by locking the knob spindle in the proper direction so that, in the event that the spring should be broken and the weight also rendered inoperative for any reason, the latch may nevertheless be operated. In actual 45 practice, I will generally omit the spring as it is used primarily to supplement the action of the weight and may be omitted entirely without rendering the device inoperative. A guide rib or way 24 will be provided within the lock case so as to support the 50 latch and guide the same in its movements, and this rib or guide will terminate short of the extreme forward position of the tooth 22, as clearly shown in Figs. 4 and 8.

It will, of course, be understood that 60 when the lock is arranged within a mortise, as illustrated in Figs. 1, 2, 4 and 6, the latch bolt is more or less inaccessible and a dead latch which depends for its success upon direct engagement with the bolt, cannot be 65 easily employed. In this event, I provide

the dead latch illustrated in Figs. 2, 3, 4, 5 and 6 which comprises a casing 25 secured to the inner face of the door and constructed with openings 26 to register with the openings provided in the door and the lock case 70 75 for the knob spindle. Within this case a hub 27 is secured upon the knob spindle 5 and this hub plays within an opening 28 in a gravitating holding member 29, a notch 30 being provided in the forward end wall 75 of the said opening to be engaged by a tooth or lug 31 on the said hub 27. The holding member 29 is a large weight resting upon the lower wall 32 of a recess 33 within the casing 25 and the said lower wall is inclined forwardly so that the weight of the member 29 will tend to retain it at the front end of the recess 33, as shown in Fig. 1, in which position the notch 30 will be out of engagement with the tooth or lug 31 and the 80 knob spindle may rotate. A handle 34 is fixed in the lower edge of the holding block or plate 29 and projects through a slot 35 in the lower wall of the casing 25 so that the holding body may be shifted from one 85 end to the other end of the casing, and the said slot also serves as an escape opening for any dust or dirt which may work into the casing and tend to collect therein. It will be readily understood that when it is 90 desired to hold the latch bolt against opening movement, the handle 34 is pushed toward the inner end of the casing 25 and the notch 30 thereby brought into engagement with the lug 31, as clearly shown in Fig. 3, 100 so that the rocking of the knob spindle will be prevented inasmuch as the upper and lower edges of the weight or holding block 29 bear against the flat upper and lower walls of the recess 33. To hold the plate or 105 block 29 in either of its set positions, I provide a thumb lever 36 which is pivotally mounted at 37 in the upper portion of the casing 25 and has its inner corner projecting through the top of the casing and suitably shaped for convenient engagement by a thumb or finger. Upon the lower edge of 110 this thumb lever, at the free end thereof, I provide a depending tooth 38 which is adapted to engage a notch 39 in the upper 115 edge of the holding block 29 or rest in the recess 40 at the upper inner corner of said block, the first-described position being illustrated in Fig. 3, while the last-described position is illustrated in Fig. 1. It will be 120 readily understood that this construction permits the dead latch to be set or released as may be desired and it will be held in either position until the parts are manually manipulated from the interior of the 125 building.

The dead latch arrangement just described is particularly designed for use when the lock is applied to a door as a mortise lock. When, however, the lock is applied 130

as a rim lock, this described dead latch arrangement is omitted and instead of the same I employ the thumb lever 41 which is pivotally mounted in the upper end of the lock case 4 and is constructed with an angular corner 42 adapted to enter the recess 16 in the latch bolt. By reference to Fig. 8, it will be noted that when the shoulder or angular corner 42 is in engagement with the recess 16, the latch bolt 11 cannot be withdrawn and to hold the thumb lever in this position against accidental release by chance blows, I provide the dog 43 which is also pivoted in the upper portion of the lock case 4 between the thumb lever and the front of the lock case and is provided on one face with a recess 44 and a rib 45 adapted to ride over and engage a spur or rib 46 on the side of the thumb lever, as clearly shown in Fig. 8. In this position, in order to release the thumb lever, it is necessary to first disengage the dog 43 and for convenience in releasing the dog, I provide the same with a lateral shoulder 47 which will furnish a base or gripping surface for engagement by the thumb of the operator. It will also be noted that the thumb lever is substantially L-shaped so that it has an arm projecting above the lock case against which the thumb or finger may easily press so that the lever may be swung in either direction as circumstances may demand. When it is desired to permit release of the latch bolt, the thumb lever and the dog 43 are swung to the position shown in dotted lines in Fig. 5, in which the free end of the dog bears against the inner end of the thumb lever and engages a transverse shoulder 48 on said lever to prevent the same accidentally dropping into engagement with the latch bolt. Of course, it will be understood that when the lock is applied as a mortise lock, the thumb lever 41 and the dog 43 may be removed but this is not necessary as the mortise in the door may be made sufficiently large to accommodate them.

A partition 49 is provided within the lock case 4 below the gravity dog 20 and is shaped, as shown clearly in Fig. 4, to receive the lower forward corner of said dog when the same is in its lowest position. Below the said partition, the key bolt 50 is slidably mounted in the lock case and rests upon the lower wall of said case, said wall being inclined rearwardly, as shown at 51, so that the bolt will tend to remain in a retracted position under the influence of gravity. A dust escape opening 52 is provided through the lower wall or end of the lock case so as to permit the escape of any dirt or dust that may accumulate therein. The bolt is constructed near its rear end with a transverse shoulder 53 adapted to engage a projection 54 on the inner wall of the lock case and be thereby limited in its retracting movement, and a transverse shoulder 55 is provided on the under side or edge of the bolt to engage a shoulder 56 on the lower wall of the lock case and thereby limit the projecting movement of the bolt. The projecting movement of the bolt is further limited by the transverse shoulder 57 at the top of the bolt near the front end thereof, and a web 58 extends longitudinally of the bolt from the front end thereof to the rear end, the said web being of less width than the bolt so that a space is provided at each side of the web in which the wards of a key may play. A transverse opening 59 is formed through the bolt and the said web 58 and the upper wall of this opening is defined by a substantially inverted V-shaped notch 60 formed in the lower edge of the web. On one side of the bolt, I form a step 61 which is adapted to be engaged by the reduced front end 62 of a tumbler 63 which is pivoted at its inner or rear end upon the side of the partition 49, and a spring 64 may be secured upon the partition so as to bear upon the upper edge of said tumbler and insure its engagement with the bolt at all times. When the bolt is retracted as shown in Fig. 4, the reduced end of the tumbler fits over the step 61 and rests upon the upper or tread surface of the step. When, however, the bolt is projected, the extremity of the tumbler drops into engagement with the riser portion of the step and thereby serves to prevent retraction of the bolt. On the opposite side of the bolt, a ledge 65 is provided at the side of the web 58 and a tooth or spur 66 is located on this ledge between the ends of the same. A tumbler 67 is pivoted at its inner rear end on the side of the partition 49 and the free end of this tumbler is constructed with a notch 68 and a hook or bill 69. When the bolt is retracted, the tooth or spur 66 will be engaged in the notch 68 and will, consequently, be held against movement in either direction. When a proper key, however, has been inserted and manipulated, the bolt will be projected and the hook or bill 69 will drop behind the lug, tooth or spur 66 and will, consequently, aid the tumbler 63 in holding the bolt projected so that the door will be held locked. The key to release the lock will, of course, be fitted to the dimensions of the tumblers 67 and the wall of the notch 60 in the bolt, and slight variations in the proportions of these parts will render any particular lock inoperative to any key except the one fitted especially to it. The key will be constructed with a notched wing so that when it is inserted through the keyhole 70 and turned as indicated by dotted lines in Fig. 4, the notched edge of the wing will ride upon the rear wall of the notch 60 and will engage 130

the front wall of the same so as to exert a push upon the bolt through the web 58. The edges of the wing at the sides of the notch will bear against the under edges of the respective tumblers and will release the same so that the bolt may be projected, and continued movement of the key will, of course, release the tumblers so that they will drop into engagement with the bolt to hold it in the locked position. Rotation of the key in the opposite direction will first release the tumblers from the bolt and will then ride against the wall of the notch in the web so as to retract the bolt, as will be readily understood.

From the foregoing description, taken in connection with the accompanying drawings, it will be seen that I have provided a very efficient lock which will thoroughly guard a door against unauthorized opening from the outside. The bolts are controlled by the force of gravity and are not dependent upon the action of springs which are apt to be broken and ordinarily thereby render a lock unusable. The holding dog is so disposed that it will act positively upon the latch so as to normally project the same and will work on the latch with very little friction. While I have disclosed a construction of knob spindle especially designed to prevent unauthorized withdrawal of the same from the lock, the ordinary knob spindle now in general use may be employed if preferred. The lock may be applied to a door without any change either as a rim lock or as a mortise lock, although when applied as a mortise lock the supplemental casing and dead latch should be used. By employing tumblers at opposite sides of the key bolt, I make it impossible to unlock the door by the use of a bent wire or a nail or any ordinary skeleton key. The ordinary lock strikes may

be used in connection with my lock whether the lock be applied as a rim or a mortise lock.

Having thus described the invention, what is claimed as new is:

1. In a lock, a symmetrical flat-faced bolt having a transverse opening to accommodate a knob spindle and provided with notches in the opposite longitudinal walls of said opening, the bolt being further provided with a notch in each longitudinal edge at its inner end and with a recess in each longitudinal edge intermediate its ends.

2. In a lock, the combination of a casing, a bolt slidably mounted therein and provided with a recess in its upper edge, means for projecting or retracting the bolt, a thumb lever pivoted in the casing above the bolt and adapted to engage the recess in the upper edge thereof, and a dog pivoted in the casing above the bolt and adapted to engage the thumb lever in all of its positions whereby to hold the same out of or in engagement with the bolt.

3. In a lock, the combination of a lock case, a bolt slidably mounted therein, means for projecting or retracting the bolt, the bolt having a V-shaped recess in its upper edge, a thumb lever mounted above the bolt and adapted to engage the said recess, said thumb lever being provided with a rib on one side and a transverse shoulder at one end, and a dog having a groove in one face adapted to engage the said rib to hold the lever in engagement with the bolt and having its end adapted to bear against the end of the lever and engage the transverse shoulder to hold the lever out of engagement with the bolt.

In testimony whereof I affix my signature.

ORION K. TILLMAN. [L. S.]
